(57) **CLAIM**

The ornamental design for a headlight assembly for a truck, as shown and described.

DESCRIPTION

FIG. 1 is a front left perspective view of the headlight assembly for a truck.

FIG. 2 is a front left perspective view of the headlight assembly in FIG. 1.

FIG. 3 is a left view of the headlight assembly in FIG. 1.

FIG. 4 is a right view of the headlight assembly in FIG. 1.

FIG. 5 is a top view of the headlight assembly in FIG. 1.

FIG. 6 is a front view of the headlight assembly in FIG. 1.

FIG. 7 is a back view of the headlight assembly in FIG. 1; and,

FIG. 8 is a bottom view of the headlight assembly in FIG. 1.

The broken lines of the figures showing additional portions of the truck are included for the purpose of illustrating environmental structure and form no part of the claimed design.

The truck includes a cab and a chassis behind. The chassis may be fitted with a variety of different bodies or implements. The figures may not include views from all directions. When absent, those views may represent mirror images of existing views or may provide no additional aspects of the claimed ornamental design. Mounting brackets and other features that provide no additional ornamental aspects of the claimed design may also not be included in the figures.

1 Claim, 7 Drawing Sheets
